(57) **CLAIM**

The ornamental design for a funeral casket, as shown and described.

DESCRIPTION

FIG. 1 is a top plan view of a funeral casket, showing my new design;

FIG. 2 is a left side elevation view thereof, the right side being a mirror image;

FIG. 3 is a front elevation view thereof, the rear view being a mirror image; and,

FIG. 4 is a perspective view thereof.

The bottom of the coffin is flat and unornamented.
